[57] **CLAIM**

The ornamental design for a prismatic light-transmitting panel, as shown and described.

DESCRIPTION

FIG. 1 is a bottom plan view of a prismatic lighting panel embodying my new design, the design shown in the upper left-hand corner thereof being understood to cover the entire lower face of the panel;

FIG. 2 is an enlarged section of the panel of FIG. 1, also shown in bottom plan;

FIG. 3 is a view in left edge elevation, as viewed in FIG. 2, thereof;

FIG. 4 is a view in right edge elevation, as viewed in FIG. 2, thereof;

FIG. 5 is a view in upper edge elevation, as viewed in FIG. 2, thereof;

FIG. 6 is a view in lower edge elevation, as viewed in FIG. 2, thereof; and

FIG. 7 is a top plan view of the panel of FIG. 1.

FIG. 1
